GRAPPLE

Clarence J. Reigh, Altoona, Pa., assignor to The Pennsylvania Railroad Company, Philadelphia, Pa., a corporation of Pennsylvania

Application January 2, 1951, Serial No. 203,883

18 Claims. (Cl. 294—67)

1

This invention relates to a grapple for engaging and lifting load objects, and more particularly relates to a grapple carrying load engaging elements effective alternately to engage and disengage the load in response to the bodily movement of the grapple itself, or of parts thereof.

Conventional load hoists have ordinarily been provided with independently actuated load engaging means such as hooks or the like. For example, solenoid-operated load engaging hooks have been employed for lifting and transporting conventional L. C. L. containers from place to place between trucks, railroad cars, platforms, and the like. Other hook-actuating means, such as electric and other motors, have also been used. These are objectionable in that the motors or solenoids which serve to operate the load engaging hooks are very heavy, particularly for use in heavy duty grapples. The weight of such actuating means is necessarily carried by the hoist, and substantially reduces the effective lifting capacity of the hoist.

Moreover the grapple-operating means heretofore employed are generally operated independently by the hoist operator, without relation to the operation of the other parts of either the grapple or the hoist. Such operation is subject to error in that, due to accident or inadvertence, the necessary steps are not always carried out in their proper sequence.

Heavy loads are handled and lifted by gripping the load at several spaced points, often located at the corners of the load. With conventional apparatus it is often difficult for the grapple operator to align the grapple with the load and to determine whether or not effective engagement has been attained at all such spaced points. Failure properly to grip the load before lifting has resulted in damage to the load, to the containers therefor, and even to the grapple itself.

Solenoid-actuated load engaging hooks are subject to the further objection that a large amount of electricity is consumed in operating the solenoid. For this reason it has been the prevailing practice to energize the solenoid only for effecting movement of the load-engaging means, and to deenergize the solenoid immediately after engagement or release of the load. After effecting engagement of the load and de-energization of the solenoid, the hooks or other load-engaging means are free to move except as they are retarded by reason of friction or other engagement between the hooks and the load. Occasionally external forces are accidentally applied

2

to the hooks after the load has been lifted, disengaging the grapple and damaging the load.

It is accordingly one object of the present invention to provide an efficient and economical grapple. Another object of the invention is to provide a grapple having load-engaging means of minimum weight. It is a still further object of the invention to provide a grapple having load-engaging means which operate in accordance with a fixed sequence of steps dependent upon the movement of the grapple itself. Still another object is to provide mechanical means for aligning the grapple with the load, and for automatically operating the load-engaging means when the grapple contacts the load. It is a still further object of this invention to provide positive locking means for maintaining the load engaging hooks of the grapple in fixed position when the load is supported by the grapple. Other objects and advantages of the invention, including simplicity and economy, and the convenience and economy of operation of the same, will appear in further detail hereinafter.

In summary, the foregoing and other objects are attained by the provision of a grapple comprising a pair of frame members movable relative to one another, load engaging means mounted on one of said frame members, cam operated means actuated by movement of the frame members toward and away from one another to move said load engaging means for engaging and releasing the load, and means also operative in response to the relative movement of the frame members for alternately activating and inactivating said cam means.

Of the drawings:

Fig. 1 represents a side elevation of a grapple which constitutes one form of the invention, the grapple being suspended above the load which is here represented in the form of a standard L. C. L. container;

Fig. 2 represents a similar side elevation of the grapple and container, showing the position assumed by the parts of the apparatus when it engages the load;

Fig. 3 represents a side elevation similar to Figs. 1 and 2, the grapple having engaged the container, and the grapple and container being suspended from the hoist;

Fig. 4 represents a further view similar to Figs. 1-3, indicating the position assumed by the grapple when the container is lowered and deposited upon an independent support;

Figs. 5, 6 and 7 represent sectional views taken as indicated by the lines and arrows V—V, VI—VI

and VII—VII, respectively, which appear in Fig. 2;

Fig. 8 represents a view in perspective of one specific form of cam means in accordance with the invention;

Fig. 9 represents a view in perspective of one form of load engaging means in accordance with the invention;

Fig. 10 represents a fragmentary side elevation of a modified form of load engaging element; and

Fig. 11 represents a view in perspective of the load engaging element shown in Fig. 10.

It is to be expressly understood that the embodiment of the invention selected for illustration in the drawings constitutes one preferred embodiment thereof, and that the invention is also capable of assuming a wide variety of other forms not shown.

Having reference more particularly to Figs. 1-6 of the drawings, it will be observed that the specific grapple selected for illustration includes a pair of rectangular frame members 10, a collapsible linkage in the form of lazy tongs 11 pivotally connected to both frame members 10, a set of load engaging elements or hooks 12 slidably mounted on the lower frame member 10 for engagement and release of the load L, and cam operating means comprehensively designated 13, which serve to move the hook elements 12 in accordance with a definite sequence in response to relative movements of the frame members 10. The upper frame member 10 carries pulley wheels 14 accommodating the cable 15 which is attached to a conventional hoist (not shown) for raising and lowering the entire grapple assembly and thereby effecting the movements of the hook elements 12.

The frame members 10 include four beams 16 arranged at right angles to one another, and connected together at their ends. Beams 16 are reinforced by a pair of centrally disposed cross beams 17.

Attached to the beams 16 are the pairs of fixed brackets 20, disposed one above the other on the respective beams 16, which serve as connectors for the scissor bars 21 of lazy tongs 11. One of each vertical pair of brackets 20 has a pair of aligned slots 22 through which a pin 23 is projected, each scissor bar 21 being apertured for pivotal connection on said pin 23. The scissor bars 21 are crossed and pivotally joined at their centers, and each is also pivotally connected by means of pins to the opposed bracket 20 of the pair. Each scissor bar 21 thus has one end pivotally connected to one frame member and the other end pivotally connected on a sliding pivot to the other frame member which occupies the same vertical plane, providing a collapsible linkage whereby the lower frame 10 may be suspended from the upper frame 10 in such manner that the frames have capacity for movement toward and away from one another. The channel shaped limit pieces 24 are pivotally mounted to depend from the point of intersection of the scissor bars 21, and serve to limit the extent of movement of each frame 10 away from the other.

A rigid rod 25 is mounted on the lower frame member 10. Also on the lower frame member 10, spaced at points adjacent the rod 25, are a pair of limit pins 26. Opposed pairs of grapple centering arms 27, the arms of each pair being connected at their free ends by the transverse centering bars 30, are pivotally mounted on the rod 25 and depend therefrom. As will be apparent,

the limit pins 26 are positioned for contact with the edges of the upper portions of the arms 27 to limit the extent of downward movement of the free ends of arms 27. The transverse centering bars 30 have load engaging surfaces constructed and arranged to contact the back surfaces 31 of container-hooks 32 of the load, thereby centering the grapple in relation to the load. The transverse centering bars 30 have spaced indentations 33 providing another set of opposed hook engaging surfaces, spaced closer to one another, for use in connection with standard containers having container-hooks 32' the backs 31' of which are correspondingly spaced, see Figs. 2 and 6. Thus the transverse centering bars are capable of acting as centering devices for use in connection with different load pieces having hooks or other upstanding elements spaced at different distances.

The transverse rod 25 also carries a standard load lifting hook 34 which may operate together with or independently of the principal load engaging elements of the invention, for grasping and lifting a load.

The slideable load engaging elements of the structure are the hook elements 12 which are formed integrally with the sliding bars 35. Each bar 35 is disposed substantially horizontally along a lower frame member 10, for sliding movement within the channels formed by the beams 16. As indicated particularly in Fig. 9 of the drawings, each sliding bar 35 carries a spaced parallel bar 36 carrying an upwardly projecting support 37 on which a pin 40 is rigidly mounted.

The rest pieces 38, 38' which are attached in fixed positions at the corners of the lower frame member 10, are spaced for engagement upon the upper edges of hooks 32 and have side projections 39, 39' which bear against the outer side surfaces of the hooks 32, 32' to restrain the grapple against movement sidewise of the load when the load is engaged by the grapple. The hook engaging edges at the bottom of rest pieces 38, 38' also coat with the load-engaging hook element 12 to provide gripping action above and below each container-hook 32, 32', holding each container-hook securely in place as the load is lifted and carried.

Each rest piece 38, 38' carries a set of downwardly disposed projections 39, 39' for use in connection with standard containers having different spacing for container-hooks 32 and 32', as will be apparent.

Spaced upon the upper frame member 10 in positions corresponding to the sliding bars 35, are the rigid plates 41 and 42 which are parallel and spaced apart by spacer plate 43. As indicated more particularly in Fig. 8 of the drawings, the plates 41, 42, 43 are held together and secured to the base plate 44 by the flush bolts 45. Each base plate 44 is bolted to one of the upper beams 16.

The bar 36 fits between the plates 41 and 42. Plate 41 which is cut away at corner 50 for the purpose of facilitating the assembly of the structure, is disposed between the bars 35 and 36.

The pin 40 is mounted in the track formed by the aligned vertical slots 46 and the angled slots 47 which are formed in the plates 41, 42 and connected at their upper ends on each individual plate 41 and 42. It will be observed that additional substantially triangular portions of the plates 41 and 42 are cut away at the intersection of the slots 46 and 47 to provide space for limited free movement of pin 40 above the slot 47. Ac-

cordingly plates 41, 42 have substantially horizontal and vertical cam edges 48, 49.

Referring to Fig. 7 of the drawings, it will be observed that a pin 51 is screwed into the plates 41, 42, 43. Pivotally depending from pin 51 is a swinging switch plate 52, which is maintained in position by spring 53, disc 54, and cotter pin 55. Switch plate 52 is cut away centrally to form an opening bounded by a pair of cam following edges 56, 57, and a pair of cam edges 60, 61. The cam following edges 56, 57 serve to swing each switch plate 52 about its pivot pin 51 in response to movement of pin 40, thereby placing the cam edges 60, 61 in position to guide the pin 40 for travel alternately in vertical slot 46 and in the angled slot 47, as will appear in further detail hereinafter. The extent of swinging movement of the switch plate 52 is limited by the stationary limit pins 63, 64.

Referring now particularly to Figs. 10 and 11 of the drawings, the modified load engaging hook 65 there represented is pivotally suspended from the rigid stationary mount 66, with capacity to swing about the pivot 67. The lever arms 10 of load engaging hook 65 have aligned vertically disposed slots 71 and the sliding bar 35' carries a pin 72 slidably mounted in the slots 71. Accordingly the sliding movement of bar 35' serves to swing the curved rods 73, 74 inwardly and outwardly about the pivot 67 for engagement and release of the load, as indicated in Fig. 10. The curved rod 73 has a hook engaging bar 75 which is constructed to engage a container-hook 32 in the position represented in dot-dash lines in Fig. 10. The curved rod 74 has an offset hook engaging bar 76 which serves to engage the container-hook 32 represented in solid lines in Fig. 10. Accordingly the load engaging hook 65 is constructed for engaging and lifting different standardized containers, on which differently spaced container-hooks are mounted.

The operation of the apparatus will be apparent, reference being had particularly to Figs. 1-4 of the drawings. Assuming it is desired to pick up the container L and to redeposit this container at another location, the grapple is lowered over the container with all parts positioned as indicated in Fig. 1, the hook elements 12 being positioned at their extreme outer positions, away from the center of the lower frame member 10. Accordingly the pins 40 which operate the load engaging hook elements 12 are at the lower ends of the angled slots 47 of plates 41 and 42. As the grapple is lowered, the transverse centering bars contact and slide along the top of the container L, ultimately engaging the backs 36 of the hooks 32, centering the grapple in relation to the container L. The rest pieces 38 then contact the tops of the container-hooks 32. Up to this point the scissor bars 21 are at maximum extension, as governed by channel pieces 24, due to the weight of the lower frame member 10. However further lowering by the hoist permits the upper frame member 10 to move downwardly while the lower frame member 10 is supported on the container-hooks 32 and remains stationary, thereby collapsing the scissor bars 21. Moreover the relative movement of the upper and lower frame members 10 causes the upper edges of the angled slots 47 to exert force in sidewise direction on the pins 40 thereby moving them to the positions indicated in Fig. 2. The angled cam surface 60 of switch plate 52 assists in urging pins 40 to the extreme positions directly above vertical slots 46. This moves the hook elements 12 toward each

other, engaging the container-hooks 32 of the container L. Lifting force is then applied to the hoist and the upper frame member 10 is moved upwardly while the lower frame member 10 remains in position due to its own weight, and to the weight of the container L. The vertical track 46 is accordingly drawn upwardly past the stationary pin 40. Since the vertical track 46 is inactive the pin 40 remains in position and the hook elements 12 do not move. Moreover the hook elements 12 are locked against movement in a sidewise direction while the pin 40 is in the vertical slot 46. As the plates 41, 42 and switch plate 52 are drawn upwardly the pin 40 contacts the cam follower edge 56 thereby swinging the switch plate 52 about pivot pin 51 to the position indicated in Fig. 3. The container L is then lifted and transported by means of the hoist to the desired location, all parts being then in the positions shown in Fig. 3.

For depositing the container L at the desired location, the hoist lowers the grapple until the weight of the container L is supported from the bottom. Upon further lowering, the weight of the upper frame member 10 causes it to move toward the lower frame member 10 which remains stationary. This moves the plates 41, 42 and switch plate 52 downwardly bringing the cam edge 61 of switch plate 52 into contact with pin 40. Pin 40 is accordingly moved to the side and the attached hook elements 12 slide in a direction away from one another, passing out from beneath the container-hooks 32 and releasing the load, all as indicated in Fig. 4 of the drawings.

Upon raising the grapple the upper frame member 10 moves upwardly while the lower frame member 10 remains stationary by reason of its own weight. Accordingly the plates 41, 42 are drawn past pin 40 which slides along the vertical edges 49 of plates 41 and 42. Upon further lifting the cam follower surface 57 of swinging switch plate 52 contacts pin 40, swinging the switch plate 52 to the position indicated in Fig. 1 as the angled slot 47 moves the pin 40 sidewise to the position of Fig. 1. Also by reason of this further movement of pin 40 under the influence of the lower edge of angled slot 47, the hook elements 12 are moved to the extreme position, away from one another, preparatory to engaging another load object, to be handled in the manner previously indicated.

Therefore it will be apparent that the upper and lower edges of the angled slots 47 represent the active elements of a cam mechanism since these are effective in moving a cam follower which is here illustrated in the form of the pin 40. Further, the substantially vertical slots 46 represent the inactive elements of the cam mechanism in that they are ineffective to move the pin 40. Moreover the switch plate 52 constitutes means for activating and inactivating the cam mechanism since the switch plates 52 serve to guide the pin 40 alternately to the inactive and to the active cam elements. The switch plate 52 is operative in response to the relative movement of the frame members 10 in that it is swung about its pivot by the pin 40 when the frame members are moved toward or away from one another.

It will be appreciated that, while I have referred to the members 10 as "frame" members, this does not imply any restriction as to size or shape. It is intended that this term shall be construed in its broad or functional sense rather than in a limited or structural sense, since frame

or other body members of widely variable character may be substituted for the frame members shown in the annexed drawings.

While I have described my invention with reference to specific embodiments thereof, it will be apparent to those skilled in the art that various changes other than those referred to above may be made in the form of the device, that equivalent elements may be substituted for those illustrated in the drawings, and that certain features of the invention may be used to advantage independently of the use of other features, all within the scope and spirit of invention as defined in the annexed claims.

Having thus described my invention, I claim:

1. A grapple comprising a pair of frame members moveable relative to one another, lazy tongs connecting said frame members together, load engaging means on one of said frame members, cam means mounted on one of said frame members, a cam follower connected to said load engaging means and actuated by said cam means in response to relative frame movement for effecting engagement and release of the load, and a selective element in the form of a switch pivotally mounted on one of said frame members, said switch being actuated by the movement of the cam follower to alternately activate and inactivate said cam means.

2. A grapple comprising a pair of frame members moveable relative to one another, lazy tongs connecting said frame members together, load engaging means on one of said frame members, cam means in the form of a plate having a pair of interconnected angled passages mounted on one of said frame members, a cam follower constructed and arranged to move in said passages, said cam follower being operatively connected to the load engaging means to effect engagement and release of the load while travelling in one of said angled passages, said cam follower having capacity to move in the other angled passage without effecting engagement or release of the load, and a switch normally disposed on one of said frame members in the path of advancement of the cam follower to alternately direct the follower for movement in different ones of said angled passages, thereby selectively activating and inactivating said cam means.

3. A gravity operated grapple comprising a pair of frame members one above the other, collapsible means connecting the frame members together, load engaging means on one of said frame members, cam means on one of said frame members including a substantially vertical track and an angled track connected to the vertical track above its lower extremity, a cam follower attached to said load engaging means and constructed for movement in the tracks of said cam means, and switch means on said cam means for directing the cam follower for movement alternately in the substantially vertical track and in the angled track.

4. A grapple comprising a pair of frame members one above the other, a collapsible linkage connecting the frame members together, load engaging means on one of said frame members, cam means on one of said frame members including a substantially inactive track and an active track connected to the inactive track, a cam follower attached to said load engaging means and constructed for movement in the tracks of said cam means, whereby the position of the load engaging means is changed in response to movement of the cam follower in the

active track, switch means in the form of a swinging plate pivotally mounted on a pivot fixed relative to said cam means, said swinging plate having a passageway in which the cam follower moves, means for limiting the extent of swinging movement of the swinging plate and means on the swinging plate passageway for contacting and directing the cam follower for movement alternately in the active and inactive tracks of the cam means, whereby the cam means is alternately effective and ineffective to move said load engaging means.

5. A gravity operated grapple comprising upper and lower frame members, a collapsible linkage connected to both said frame members with capacity to suspend the lower frame member from the upper frame member, a hoist attached to the upper frame member, load engaging means on the lower frame member, cam means on one of said frame members and cam follower means on one of said frame members and operatively connected to the load engaging means with capacity to shift the load engaging means in response to relative vertical movement of the frame members, thereby engaging and releasing the load, said upper frame member having sufficient weight to overcome friction to move the load engaging means by operation of gravity alone when the grapple is lowered upon the top of the load, and the lower frame member having sufficient weight to move the load engaging means when the upper frame member is lifted by means of the hoist upwardly from the load.

6. A grapple comprising a pair of frame members moveable relative to one another, a collapsible linkage connecting said frame members and maintaining said frame members substantially parallel, load engaging means in the form of opposed hooks slidably mounted on one of the frame members for movement toward and away from one another, said hooks being constructed and arranged to grip the load at the top thereof, cam means on one of said frame members, switch means on one of said frame members for activating and inactivating said cam means, cam follower means actuated by said cam means in response to relative movement of the frame members when the cam means is activated, said cam follower means being attached to the opposed load engaging hooks to move said hooks toward and away from one another to engage and release the load, and said switch means also being operative in response to the relative movement of the frame members for alternately activating and inactivating said cam means.

7. A grapple comprising a pair of frame members moveable relative to one another, a slide bar mounted on one of said frame members for sliding movement thereon, a load engaging hook attached to said slide bar, a cam follower fixed on said slide bar, cam means mounted on the other of said frame members with capacity when activated to operate said cam follower, said cam means being actuated by relative movement of the frame members toward and away from one another to move said cam follower, slide bar and load engaging hook for engaging and releasing the load, and cam controlling means connected to said cam means and operative in response to the movement of the cam follower for alternately activating and inactivating said cam means.

8. A grapple comprising a pair of frame members moveable relative to one another, load engaging means mounted on one of said frame members, a cam follower attached to said load

engaging means, cam means on the other of said frame members, said cam means including an active element having capacity to move the cam follower in response to relative movement of the frame members and an inactive element ineffective to move the cam follower when the frame members move relative to one another, a swinging switch on one of said frame members adjacent said cam means, an internal passage in said swinging switch wherein the cam follower is disposed, guide means on the swinging switch for directing the cam follower for association alternately with the active and inactive elements of the cam means, and guided means on the swinging switch disposed in the path of travel of the cam follower, for moving the swinging switch in response to the movement of the cam follower.

9. A grapple comprising a pair of relatively moveable frame members mounted one above the other, brackets on the respective frame members, crossed scissor bars each mounted on a fixed pivot to one of said brackets and on a horizontally slidable mount to the other of said brackets, whereby the frame members are held substantially parallel during the course of movement of the frame members toward and away from one another, load engaging means mounted on one of said frame members, cam operated means on one of the frame members actuated by movement of the frame members toward and away from one another and connected to said load engaging means with capacity to move said load engaging means for engaging and releasing the load, and switch means on one of said frame members operative in response to the relative movement of the frame members for alternately activating and inactivating said cam means.

10. The invention as defined in claim 9 further characterized by the provision of restrictive means on said scissor bars limiting the extent of movement of the frame members away from one another.

11. A grapple for engaging a load having an upstanding hook thereon, comprising a pair of frame members moveable relative to one another, load engaging means mounted on one of the frame members and moveable relative thereto for operative engagement of a lower portion of the hook, fixed means on said one of the frame members for engaging an upper portion of the hook thereby providing positive gripping action thereon, cam means on one of said frame members actuated by movement of the frame members toward and away from one another, said cam means being connected to said load engaging means and effective when activated to move said load engaging means for engaging and releasing said hook, and switch means on one of said frame members also operative in response to the relative movement of the frame members for alternately activating and inactivating said cam means.

12. A grapple comprising a pair of frame members one above the other, a collapsible linkage connecting said frame members together and suspending one frame member below the other, the lower frame member including a channel having outwardly directed flanges, a sliding bar mounted between said flanges for movement on said lower frame member, a load engaging element attached to said sliding bar, lifting means attached to the upper frame member to raise and to permit gravity lowering thereof, whereby the upper frame member may be moved toward and away from the lower frame member, cam oper-

ated means on one of said frame members operative in response to relative movement of the frame members and connected to said sliding bar with capacity to move said sliding bar to engage and disengage the load engaging element and the load, and switch means supported on one of said frame members also operative in response to the relative movement of the frame members for alternately activating and inactivating said cam means.

13. The invention as defined in claim 12, further characterized by the fact that the load engaging element is in the form of a support plate rigidly mounted on the slide bar for sliding movement in line with the lower frame member.

14. A grapple comprising a pair of frame members one above the other, a collapsible linkage connecting said frame members together and suspending one frame member below the other, the lower frame member being in the form of a channel having flanges thereon, a sliding bar mounted between said flanges, a fixed mount on said lower frame member, a load engaging element pivotally suspended from said mount, a vertical slot in said load engaging element, a fixed pin on the slide bar disposed within said slot to actuate swinging movement of the load engaging element about its pivot in response to the movement of the sliding bar, means attached to the upper frame member to raise and to permit gravity lowering thereof, whereby the upper frame member may be moved toward and away from the lower frame member, cam operated means supported by one of said frame members and operative in response to relative movement of the frame members to move said sliding bar to effect pivotal movement of the load engaging element to engage and disengage the load, and switch means on one of said frame members operative in response to the relative movement of the frame members for alternately activating and inactivating said cam means.

15. A grapple comprising a pair of body members movable relative to one another, load engaging means carried by one of said body members, cam means on one of said body members having active and inactive cam portions, cam follower means supported by one of said body members and operatively connected to said load engaging means with capacity to actuate the same, and switch means on one of said body members, said switch means having a cam surface arranged to contact said cam follower and switch it from said active cam portion to said inactive cam portion, and said switch means also having a cam follower surface that is movable relative to said cam means and arranged to be moved by said cam follower for resetting said switch means relative to said cam means.

16. A gravity operated grapple comprising upper and lower frame members, suspension means connected to both said frame members to suspend the lower frame member from the upper frame member with said lower frame member having capacity to reciprocate up and down relative to said upper frame member, restrictive means preventing relative rotation of the lower and upper frame members, hoisting means for raising and lowering the upper frame member, load engaging means frictionally carried by the lower frame member, cam means on one of said frame members and cam follower means on one of said frame members, said cam follower means being operatively connected to the load engaging means with capacity to shift the load engaging

11

means in response to relative movement of the frame members, thereby engaging and releasing the load, said upper frame member having a weight greater than the existing frictional forces which oppose the shifting movement of the load engaging means, whereby the upper frame member has capacity to shift the load engaging means by operation of gravity alone when the grapple is lowered upon the top of the load, said lower frame member also having a weight greater than the existing frictional forces which oppose the shifting movement of the load engaging means, whereby the lower frame member has capacity to move the load engaging means by reason of its weight alone when the upper frame member is lifted upwardly from the load.

17. A load lifting device comprising a pair of body members movable relative to one another, connecting means between the body members for guiding said relative movement, load engaging means carried by one of said body members, cam means carried by one of said body members, a cam follower connected to said load engaging means and guided by said cam means in response to relative body member movement for effecting engagement and release of the load, and a selective element in the form of a switch carried by and movable with respect to one of said body members, said switch being movable with respect to its body member in response to movement of said cam follower and effective alternately to activate and inactivate said cam means in response to the movement of the cam follower.

18. A load lifting device comprising a pair of body members movable relative to one another, connecting means between the body members for

5

10

15

25
